UNITED STATES PATENT OFFICE

167,910

STOCKING

George W. Smith, Mohnton, Pa.

Application January 2, 1952, Serial No. 17,884

Term of patent 14 years

(Cl. D47—7)

To all whom it may concern:

Be it known that I, George W. Smith, a citizen of the United States, residing at Mohnton, Pennsylvania, have invented a new, original, and ornamental Design for a Stocking, of which the following is a specification, reference being had to the accompanying drawing, forming a part hereof.

Fig. 1 is a side view of a stocking embodying the design.

Fig. 2 is a rear perspective view of the lower portion of the stocking.

I claim:

The ornamental design for a stocking, as shown.

GEORGE W. SMITH.
